Atty:

UNITED STATES PATENT OFFICE.

HENRY F. COOK, OF SAG HARBOR, NEW YORK, ASSIGNOR TO THE FAHYS
WATCH CASE COMPANY, OF SAME PLACE.

DESIGN FOR A KNUURL.

SPECIFICATION forming part of Design No. 20,348, dated November 25, 1890.

Application filed June 23, 1888. Serial No. 278,051. Term of patent 14 years.

To all whom it may concern:

Be it known that I, HENRY F. COOK, a citizen of the United States, residing at Sag Harbor, county of Suffolk, and State of New York, 5 have invented and produced a new and original Design for Knurls, of which the following is a specification, reference being had to the accompanying drawings, forming a part thereof.

10 In said drawings, Figure I is a side view of a knurl having my design. Fig. II is a plan view thereof.

The leading feature of my design consists 15 in a scalloped periphery having ornamental scroll-work.

16 3 represents the annular head or knurl of a knurling-tool, having a scallop 1 or inward curvature of the periphery with gradual expanding and diminishing sections of the rim.

2 represents scroll-work on the rim. The 20 scroll-work 2 is given such form that the wider portion of the scroll occupies the space between the inward projections of the scallop, while the outer end of the scroll is formed on the narrow part of the knurl opposite such 25 inward projections of the scallop.

Having thus described this invention, what I claim as new therein, and desire to secure by Letters Patent, is—

A design for knurls, substantially as herein 30 described and shown.

HENRY F. COOK.
